UNITED STATES PATENT OFFICE.

SELBY C. CARR, OF MUSKOGEE, OKLAHOMA.

CLOSURE FOR JARS AND THE LIKE.

1,033,382.

Specification of Letters Patent. Patented July 23, 1912.

Application filed April 25, 1911. Serial No. 623,285.

To all whom it may concern:

Be it known that I, SELBY C. CARR, citizen of the United States, residing at Muskogee, in the county of Muskogee and State of Oklahoma, have invented certain new and useful Improvements in Closures for Jars and the Like, of which the following is a specification.

The present invention relates to clamps 10 for holding the closures of jars, bottles, crocks, and the like, in place, and aims primarily to provide a clamp for the purpose stated which will firmly hold the closure in place regardless of temperature changes to 15 which the contents of the container may be subjected.

The invention aims further to provide a clamp of the character mentioned, the parts of which may be readily disassembled, so 20 that should one or the other of the parts become broken or worn, the entire clamp will not be rendered useless.

A further feature of the invention resides in the construction of the closure itself, it 25 being particularly well adapted for use in connection with the clamp of the invention.

For a full understanding of the invention reference is to be had to the following description and accompanying drawing, in 30 which:

Figure 1 is a vertical sectional view through the jar and its closure and showing the clamp embodying the present invention, the clamp being in position prior to operation. Fig. 2 is a similar view showing the clamp in clamping position. Fig. 3 is a view similar to Fig. 2 taken through a bottle at 15 its closure, a metal cap being used for the closure. Fig. 4 is a top plan view of the structure shown in Fig. 3. Fig. 5 is a perspective view of the clamp-lever.

Corresponding and like parts are referred to in the following description and indicated in all the views of the accompanying drawings by the same reference characters.

In the drawings there is shown, in Figs. 1 and 2 a jar, a closure and a clamp, all embodying the principles of the present invention, and in Figs. 3 and 4 a bottle 0 and its closure and clamp also embodying the principles of the invention, it being understood that the adaptation of the invention to any particular container requires

only a change in the proportions of the parts, the structure being otherwise identical in every instance. 55

The container in the accompanying drawings, is indicated by the numeral 1, and has a mouth 2 which is formed exteriorly with a shoulder 3. The closure for the container, when the container is in the form of a jar, is preferably of glass, although any desired material may be used, and is concavo-convex and disposed upon the mouth of the container with its convex side outermost. This 65 closure is indicated in the drawings by the numeral 4 and is formed with a channel 5 which is presented downwardly and outwardly and is continuous. The edge of the mouth of the container is formed with an 70 upwardly and inwardly presented bevel 6 which, when the closure is in proper position upon the container, is presented downwardly toward the channel 5, the channel being V-shaped and the bevel forming the 75 base of a triangle of which it and the walls of the channel are sides. An elastic packing ring 7 circular in cross-section, is fitted in the channel 5 prior to clamping the closure on the mouth of the container, and when the 80 closure is clamped in place, this ring will be compressed and will conform to the walls of the channel and the bevel of the mouth of the container. It will be observed that the 85 depending flange of the closure which constitutes one wall of the channel 5, is of a diameter slightly less than the internal diameter of the container mouth, so that when the closure is in place this flange will project a short distance into the mouth of the 90 container.

The clamp for holding the closure in place upon the container includes a band 8 which is of resilient sheet metal and, adjacent its ends, is bowed as at 9 to form downwardly 95 projecting arms 10 having a normal tendency to spring inwardly toward each other and provided at their extremities with hooks 11 arranged to engage with the shoulder 3 of the container at diametrically opposite 100 points. The intermediate portion of the band 8 is bowed upwardly to form a loop 12 and the band, at the ends of the loop, rests upon the upper face of the closure 4 when the band 8 is in proper position upon the 105 container and its closure and the bowed por-

tions 9 extend over the edge of the closure and the edge of the mouth of the container in spaced relation with respect thereto, and as a consequence, should the contents of the 5 container be subjected to abnormally high temperature, the expansion of the closure will be permitted, although the closure will be so firmly held in place as to prevent the leakage of the said contents. In other words, 10 the bowed portions 9 of the band allow the band to exert its full resilient clamping action on the closure. The clamp also includes a finger-lever which is indicated by the numeral 13 and is formed with a head 15 14 having a laterally projecting semi-cylindrical cam-portion 15. This portion 15 has its rounded face presented in the direction of projection of the finger-lever and its said rounded face, at the end of said portion, is 20 beveled as indicated by the numeral 16 to permit of the ready insertion of said portion into the loop 12 and between the same and the upper face of the closure. At this point it will be readily understood that the 25 finger-lever clamp is bodily removable from the band 8 and that the band is to be first disposed upon the container and closure and the cam-portion of the finger-lever then inserted in the loop in the position shown in 30 Fig. 1 of the drawings, its flat face, at such time, resting upon the upper face of the closure. After the finger-lever has been thus positioned it is pressed down to either side until it assumes the position shown in Fig. 35 2 of the drawings, at which time it will

support the intermediate portion of the band away from the closure.

Having thus described the invention what is claimed as new is:—

1. A clamp of the class described comprising a band formed at its ends to engage with a container, and a cam head having a flat and a rounded side and having a finger lever projecting from its rounded side at one end thereof only, the said head being 40 otherwise free from projections, the head being adapted to be removably inserted beneath the said band. 45

2. The combination with a container and a closure therefor, the said closure having a 50 convex upper side, of means for clamping the closure upon the container, said means comprising a band arranged at its ends to engage with the container and having its portions adjacent its ends positioned upwardly and outwardly in spaced relation to the edge of the closure and the edge of the mouth of the container, the intermediate portion of the band being formed with an upwardly presented semi-circular loop resting at its ends upon the convex side of the closure, and a finger lever having a laterally projecting semi-cylindrical cam portion 55 removably inserted within the loop. 60

In testimony whereof, I affix my signature 65 in presence of two witnesses.
